RADIATOR GRILLE

Chester L. Lewellen, Detroit, Mich., assignor to
Motor Products Corporation, Detroit, Mich., a
corporation of New York

Application March 5, 1934, Serial No. 714,207

11 Claims. (Cl. 293—54)

This invention relates to radiator grilles and refers more particularly to grilles of the type employed in association with radiators of motor vehicles.

More specifically, this invention concerns itself with that type of grille having a frame and louvers or blades secured in lateral spaced relation to each other within the frame by means of supports or bars extending transversely of the blades. One of the principal objects of this invention is to simplify the construction of grilles of the general type set forth above and reduce the cost of manufacture thereof by providing a connection between the blades and supports rendering it possible to appreciably reduce the assembly time.

In accordance with this invention expedient assembly of the blades with the bars is achieved by providing a snap engagement therebetween and it is a further object of this invention to provide such a connection wherein accidental or unauthorized removal of the blades from the bars is prevented.

Still another object of this invention resides in the provision of a construction of the foregoing character wherein the bars assume a position between the front and rear edges of the blades in the assembled relation thereof. This construction not only enhances the general appearance of the grille, but at the same time offers the possibility of supporting means in engagement with the rear edges of the blades.

With the foregoing as well as other objects in view, the invention resides in the peculiar construction of the grille which will be made more apparent as this description proceeds, especially when considered in connection with the accompanying drawing, wherein:

Figure 1 is a front elevational view of a grille constructed in accordance with this invention;

Figure 2 is an enlarged fragmentary elevational view of one of the cross supports illustrating a blade in assembled relation therewith;

Figures 3, 4, and 5, are sectional views taken substantially on the planes indicated by the lines 3—3, 4—4, and 5—5 respectively, on Figure 2;

Figure 6 is a detailed sectional view taken substantially on the line 6—6 of Figure 1;

Figure 7 is a fragmentary perspective view of one of the blades.

Figure 8 is a fragmentary perspective view of one of the bars for holding the blades in assembled relation.

Referring now to the drawing, it will be noted that there is illustrated in Figure 1, a radiator

grille 10 comprising a marginal frame 11 and a plurality of louvers or blades 12 secured in lateral spaced relation within the frame by means of suitable bars 13 extending transversely of the blades.

The cross bars 13 are preferably stamped from sheet metal to form a plurality of scallops 14 in opposite longitudinal edges thereof and the apexes of the scallops are fashioned during the stamping operation to form opposed wedge shaped ears or lugs 15. Although the bars may be bent to conform to any suitable shape of grille, nevertheless, they are substantially flat in cross-section and the lugs or ears 15 are disposed in the same plane as the body portions of the bars.

In the specific embodiment of the invention selected herein for the purpose of illustration, the blades 12 are substantially U-shaped in cross-section having the free edges thereof bent inwardly to form terminal flanges 16 and having

portions of the free edges cut away at longitudinally spaced points to form slots 17. The length of the slots 17 corresponds to the width of the cross bars 13 between the shoulders 18 formed by the wedge shaped ears 15 and the depth of these

slots is substantially equal to the thickness of the bars 13 plus the thickness of the terminal flanges 16. The width of the space between the terminal flanges 16 is substantially less than the width of the base portions of the lugs 15, but is sufficient

to receive therebetween the apexes of the wedge shaped lugs 15, and the metal from which the blades are formed possesses the inherent resiliency required to snap the terminal flanges 16 over the base portions of the wedge shaped lugs

15. Inasmuch as the length of each of the slots 17 in the blades is equal to the distance between the shoulders 18 associated with the opposed lugs 15 on the cross bars, and in view of the fact that the depth of the slots 17 is equal to the thickness

of the wedge shaped ears 15 plus the thickness of the terminal flanges 16, it necessarily follows that the portions of the latter flanges adjacent opposite ends of the slots may be snapped over the base portions of the ears in the manner clearly

shown in Figures 2 to 5 inclusive. The shoulders 18 will, of course engage the opposite ends of the slot to prevent longitudinal displacement of the blades relative to the cross bar and the width of the base portions of the ears is so determined as

to prevent lateral displacement of the blades relative to the bars. Consequently, a snug connection between the blades and cross bars results and accidental or unauthorized removal of the blades is positively prevented by virtue of the

fact that the flanges overlap the base portions of the ears. However, in the event it is desired to remove one or more of the blades from the cross bars, the terminal flanges may be spread apart sufficiently to disengage the same from the ears by inserting a suitable tool between the flanges adjacent the ears. It will further be appreciated that by reason of the foregoing construction, the portions of the cross bars attached to the blades lie in a plane between the front and rear edges of the blades. As hereinbefore stated, this feature is desirable since it enhances the general appearance of the grille and provides for supporting the grille with the rear edges of the blades in contacting relation with a surface.

It should be understood that the ears 15 are properly spaced so that when the blades or louvers are subsequently engaged therewith, the latter will naturally assume the proper spaced relationship in the assembly. The provision of the snap-on connection previously described in detail not only insures a durable grille construction, but at the same time enables the grille to be quickly assembled, and for this reason materially reduces the cost of manufacture.

The principles involved herein may be obtained by various different specific constructions and reservation is made to make such changes in the construction as may come within the purview of the accompanying claims.

What I claim as my invention is:

1. In a radiator grille, a supporting bar having a projection extending from one longitudinal edge thereof in the plane of the same, and a louver blade extending transversely of the bar and having portions shaped for snap-on engagement with said projection.

2. In a radiator grille, a supporting bar having its opposite longitudinal edges shaped to provide projections arranged in pairs spaced longitudinally of said bar with the projections of each pair disposed opposite each other in a common plane, and a plurality of louver blades having portions shaped for snap-on engagement with pairs of said projections.

3. In a radiator grille, a supporting bar having opposed projections extending in opposite directions from the longitudinal edges thereof, and a louver blade having flexible marginal edge portions fashioned for snap-on engagement with the projections aforesaid on the bar.

4. In a radiator grille, a supporting bar having opposed projections extending in opposite directions from the longitudinal edges thereof, and a louver blade substantially U-shaped in cross-section provided with means at the longitudinal edges thereof adapted for snap-on engagement with said projections.

5. In a radiator grille, a blade, a supporting

bar extending transversely of the blade and having projections extending from the longitudinal edges thereof in the same direction as the blade, and means upon said blade fashioned for snap-on engagement with said projections.

5

6. In a radiator grille, a supporting bar, a louver blade extending transversely of the supporting bar and slotted to receive the same, and projections extending from opposite longitudinal edges of the bar cooperating with portions of the 10 louver blade at the ends of the slot to secure the 10 blade to the bar.

7. In a radiator grille, a supporting bar, a louver blade extending transversely of the supporting bar and slotted to receive said bar, 15 projections extending from opposite longitudinal edges of the bar, and means on said blade at the ends of the slot fashioned for snap-on engagement with said projections.

8. In a radiator grille, a supporting bar, a 20 louver blade extending transversely of the bar and slotted for receiving the same, shoulders at opposite longitudinal edges of the bar engageable with the ends of the slot to hold the blade against longitudinal displacement, projections extending 25 from the shoulders, and means at the ends of the slot in the louver blade fashioned for snap-on engagement with the projections.

9. In a radiator grille, a supporting bar having substantially wedge shaped projections extending 30 from opposite longitudinal edges, a substantially U-shaped louver blade having terminal flanges at the free edges thereof fashioned to snap over the wedge shaped projections.

10. In a radiator grille, a supporting bar having shoulders at opposite longitudinal edges thereof, a substantially U-shaped louver blade having the free longitudinal edges thereof slotted to receive the supporting bar with the shoulders on the latter in engagement with the ends of the 40 slot, projections on said supporting bar extending from the shoulders beyond the ends of the slot in the louver blade, and terminal flanges projecting inwardly from the longitudinal edges of the louver blade at opposite ends of the slot 45 and extending in overlapping relation to the projections.

11. In a radiator grille, a supporting bar having shoulders on opposite longitudinal edges thereof, a substantially U-shaped louver blade extending transversely of the bar and slotted to receive the latter with the shoulders thereon in engagement with the opposite ends of the slot in the blade, wedge shaped projections extending from the shoulders beyond the ends of the slot, 50 and inwardly extending terminal flanges at the longitudinal edges of the louver blade fashioned to snap over the wedge shaped projections.

CHESTER L. LEWELLEN.
